IGNITER

John P. Catlin, Fairfield, Conn., assignor to Remington Arms Company, Inc., Bridgeport, Conn., a corporation of Delaware

Application October 27, 1945, Serial No. 625,090

2 Claims. (Cl. 102—73)

1

This invention relates to an improved form of igniting device which has a particularly valuable application to initiating combustion in the fire pot of an automobile torpedo.

The form of automobile torpedo conventionally employed by the naval forces employs a turbine adapted to be driven by the expansion of an elastic fluid. To this turbine is fed a mixture consisting of steam and the products of combustion of a hydro-carbon fuel. This mixture is produced by feeding compressed air and alcohol or other suitable fuel into a combustion pot where the mixture is burned with the injection of water. The water is injected to aid in controlling combustion and by its conversion to steam and subsequent expansion aids in driving the turbine.

The release valves which initiate the flow of air and fuel are ordinarily operated upon the release or launching of the torpedo from the aircraft. It has been the common practice to actuate the igniter by means of a water operated trip valve upon entry of the torpedo into the water. However, it has been observed that a considerable amount of air is entrained with the torpedo and travels with it to a considerable depth in the form of a large bubble which greatly delays the operation of any water actuated member.

In the use of such torpedoes by military aviation units, it is common practice to launch the torpedo by releasing it from aircraft flown at low altitudes over the water. In carrying out this method, the torpedo is secured by shackles in a position extending substantially longitudinally of the aircraft. The aircraft is flown at a low altitude over the water in the direction of the target and the torpedo released from the shackles to enter the water and take up its course in a direction of the target. At the time the torpedo is released from the shackles, valves are actuated for commencing the feeding of air and fuel through the fire pot to the turbine or to the engine of the torpedo. Conventionally, the ignition operation has been commenced as discussed above by the action of the water and attempts have also been made to operate the igniters prior to water entry.

On release from the aircraft, the torpedo will approach the water with a downward velocity due to the acceleration of gravity and with a forward velocity substantially equal to that of the plane. In practice, it has been observed that the torpedo generally enters the water cleanly in a somewhat nose-down attitude. In passing into the water which is a relatively dense medium, the torpedo suffers a severe deceleration and it has been

5 theorized that if the ignition operation has been commenced prior to this time the shock may snuff out the flame in the fire pot or in the igniter itself, resulting in an undesirable "cold-shot," the turbine being driven only by the expansion of the compressed air. It will be seen that it is desirable to delay firing until after water entry to allow the shock problem to be avoided and to secure a better ignition of the fuel, since in the early stages 10 of injection the mixture of air and hydro-carbon has not stabilized at proportions suitable for most effective combustion.

15 After the torpedo has entered the water, its control depends upon the actuation by automatic machinery of suitable steering rudders. At low speeds, these rudders are relatively ineffective in controlling the torpedo. It will be seen, therefore, that if the torpedo is to be brought under control along its course at the earliest possible 20 moment, it is desirable to get the engines underway and secure steerage way as soon as possible after the torpedo has entered the water. It is therefore essential that the torpedo be ignited as soon as possible after entry into the water.

25 With these factors in mind, it is an object of this invention to provide an improved igniter or aerial torpedo which will not have the undesirable characteristics of the previous igniters.

30 It is a further object of this invention to provide a torpedo igniter which functions immediately on entry of the torpedo into the water and continues to burn for a period of time adequate to insure that the combustion is well established.

35 Other objectives are to effect an increase in certainty of functioning and to provide safety means to remove the hazard from storing and handling of such igniters.

40 This invention contemplates accomplishing these objects by the provision of an inertia actuated igniter which is operated by the deceleration incident to entry of the torpedo into the water.

45 The exact nature of a particularly desirable form of the invention as well as other objects and advantages thereof will more clearly appear on consideration of the drawing, in which:

Fig. 1 is a longitudinal sectional view through the igniter.

Fig. 2 is a partial sectional view taken in the 50 same plane as Fig. 1 showing the safety or disarming pin in place.

Fig. 3 is a plan view of the mid-section of a typical torpedo, part of the outer skin being broken away to show the location of the fire pot.

Fig. 4 is an elevational view showing substan-

tially the attitude of the torpedo in relation to the aircraft just prior to entering the water.

Fig. 5 is a vector diagram illustrating roughly the relative magnitude of the velocities producing the decelerational forces applied to the parts of the torpedo on water impact.

Referring to the drawing by characters of reference, it may be seen from Fig. 4 that the usual method of launching such torpedoes is for an aircraft 1 to fly on a low and momentarily straight path in the direction of its intended target. During the interval of straight flight, a torpedo 2 is released from shackles in the torpedo bay of the aircraft and thereafter controlled by self-contained devices of relatively well-known construction on its path to the target. In common with most of the torpedoes used by the military and naval forces of the United States, the torpedo 2 to which this invention is shown applied contains in its mid-section a combustion pot 3 to which there is fed in the conventional manner, air through tube 4, hydro-carbon fuel such as alcohol through tube 5, and water through tube 6. The pot 3 is provided with an opening 7 in alignment with a suitable access port 8 which allows insertion and removal of the igniter body 9 from its space within the torpedo proper. It will be observed that the axis of the combustion pot is at substantially a right angle to a plane including the longitudinal axis of the torpedo and that the igniter body is inserted into the pot with its axis in substantial alignment with that of the pot.

Under the condition of launching illustrated in Fig. 4, the torpedo receives a downward acceleration due to the force of gravity during the period of free fall. Since it will have just been released from a swiftly moving plane, it will have a forward velocity equal to that of the plane less a negligible amount due to air friction. The torpedo is normally released from the minimum safe altitude of operation of the aircraft and the velocity due to movement of the plane is a predominating factor. As the torpedo passes into the water, which by comparison to the air, is a relatively dense medium, it will suffer a considerable deceleration. In fact, peak values of several hundred g. have been found to be relatively common at the instant of water entry. The force of inertia acting on the parts of the torpedo during deceleration may be broken down into two components—a component V due to the forward velocity of the forward torpedo and a component G due to the downward velocity produced by gravitational acceleration. The former is many times greater and the resultant decelerational force will approximate that which would be due to a component velocity such as that designated as R on the vector diagram of Fig. 5.

Referring particularly to Fig. 1, it will be seen that a preferred form of the igniter comprises a body 9 which is threaded for insertion into the opening 7 of the combustion pot. The body 9 is provided with a longitudinally extending cavity in which there may be pressed a main burning charge 10, an igniter charge 11, and a primer charge 12. It will be noted that the igniter charge is in intimate contact with the main burning charge and that the primer mixture is substantially enclosed by the igniter charge. The primer 12 is in substantial alignment with an axially extending ignition tube 13 which is threadably mounted in the cavity and serves as a housing for the firing pin 14. Se-

cured near the pointed end of the firing pin is a spring thrust bushing 15 which receives the thrust due to the spring 16 and serves to guide the firing pin in the ignition tube 13. Seated in an outwardly opening cavity at the opposite end of the body 9 is a shear plate 17 which receives the thrust of the spring 16 on its inner face and engages a shear pin 18 passing through the firing pin on its outer face.

10 Seated against the shear plate 17 and maintaining a predetermined spacing between the shear plate and a thrust plate 23 is an annular spacer bushing 22. Together, the two plates and the spacer 22 define a cavity in which an inertia weight 24 is received with capacity for relatively free movement in planes normal to the axis of the igniter and which has only a limited capacity for movement along the axis of the igniter. The thrust plate 17 is sealed against the penetration of moisture and the leakage of air or gas from within the body by a gasket or sealing ring of rubber or rubber-like material which is compressed and held in place by an outer plug 26 which serves to secure the plate against its seat 25 on the spacer 22.

In armed condition, a central opening in the outer plug is closed by a sealing screw 27 which seats upon a gasket 28. To insure that the mechanism will not be inadvertently disassembled, the outer plug may be sealed in place as by solder 29.

By reference to Fig. 2, it may be seen that for safety, the sealing screw 27 may be replaced by a safety screw 30 which is provided with a pin 31 adapted to enter an appropriate recess in the inertia weight 24 and is provided with an arming pin bar 32. It will be noted that the bar 32 has a greater lengthwise dimension than the diameter of the wrench engaging portion of the head of the body 9. Since the igniter can only be assembled to the torpedo by use of a special socket wrench, it is thereby made certain that the igniter cannot be inserted without removing the safety screw.

45 In considering the operation of the improved igniter, it has been noted that the body is inserted into the pot with its axis perpendicular to a plane containing the longitudinal axis of the torpedo. By reference to the vector diagram, it will be seen that a force R will be applied generally along the axis of the torpedo and will tend to move the inertia weight laterally in the space between the shear plate 17 and the thrust plate 23. The provision of a coned face 55 33 on the inner face of the inertia weight 24 insures that lateral movement of the weight will apply an endwise thrust to the firing pin 14. The fact that the inertia weight may depart from its central position in any direction and is symmetrically shaped on its inner face makes the orientation rotationally of the body an unimportant factor. This avoids the necessity for qualifying the thread which secures the igniter in the firing pot.

60 65 When the lateral force tending to move the inertia weight has exceeded a predetermined minimum, the force transferred to the firing pin will cause shearing of the pin 18. Spring 17 will drive the firing pin inward, thus firing the primer 12 which, in its turn, ignites the top charge 11 and the main charge 10.

70 The dimensions of the cavity in which the inertia weight is received are not particularly critical so long as no binding of the weight is permitted and the weight is required to slide in the

lateral paths without cocking to one side or the other as might be the case if the clearance was excessive. The angle of the coned face and the resistance of the shearing pin are so chosen as to hold under normal shocks such as might be incident to a rough landing of the aircraft and to positively release on water impact incident to launching from aircraft. The preferable construction shown has been found to be safe under accelerational forces of 50 g. and to fire consistently on inertia forces exceeding 100 g.

The heat of combustion and the evolution of gases due to the burning of the charges blows out and fuses the end seal 19. Preferably, the end seal 19 will have been coined to produce an annular zone 34 of reduced thickness which insures that the small center section blows out first. Since the center section is small and is of a readily melted material, it is unlikely to obstruct the turbine nozzle or blading. The relatively heavy outer ring of the end seal gives further support to the igniter charge as it functions and is then melted and blown clear. As a further aid to supporting the charges, annular grooves 35 may be placed in the outside of the ignition tube and will exert considerable holding force on the charge after the same has been pressed into the cavity of the body.

The exact composition of the charges employed is not a part of this invention and is not disclosed herein. In order that the skilled pyrotechnist may select suitable mixtures, the essential requirements are:

Igniter mixture.—The primary function of this charge is to ignite readily from the primer flash and in turn to ignite the main burning charge.

Main burning charge.—The mixture must:

1. Be hot enough to ignite and burn to completion under conditions existing in combustion pot; yet
2. Not be so hot that the mixture will detonate; and
3. Be cool enough so that the mixture will burn for a long time despite the relatively short length of the burning column prescribed by the design limitations;
4. Be stable under severe storage conditions; and
5. React with complete reliability when set off by the primer flash.

Primer mixture.—The primer mixture must be sufficiently sensitive to ignite readily when stabbed by the firing pin and must be hot enough to fire the igniter mixture with certainty.

It will be noted that the primer is in direct contact with the igniter mixture and substantially surrounded with that mixture. This makes it certain that the actuation of a properly selected primer will function the igniter mixture even under the most adverse conditions.

From consideration of the foregoing, it will be apparent that the igniter cannot function prior to water impact. Since the release of air and fuel is commenced as soon as the torpedo leaves the plane, it is also certain that a proper mixture is present in the fire pot when the igniter does

function and that delivery of a hot mixture of gases to the turbine will commence at once. This ensures that the torpedo will build up steerage way almost immediately and that control will be established in a very short distance. That this does take place is borne out by the fact that torpedoes utilizing this igniter make exceptionally shallow dives on entry into the water. This factor is of great importance in the making of airplane torpedo attacks in shallow coastal and harbor waters where the torpedo might otherwise dive into the bottom.

It is to be understood that the form of my invention herein specifically shown and described is intended only to be illustrative of a preferred embodiment and that various changes and reconstructions may be resorted to without departing from the spirit of the invention as defined in the claims herewith.

20 I claim:

1. An igniter for a torpedo comprising a body, a pair of flat guide surfaces formed in said body in spaced, facially parallel relationship; an inertia block received in said body between said 25 guide surfaces with capacity for sliding movement parallel to said surfaces, the side of said block in engagement with one of said surfaces being provided with a conical recess; a firing pin slidably mounted in said body and having a terminal end projecting through said one of said surfaces into said conical recess; shearable means retaining said firing pin with said terminal end projecting into the conical recess; spring means in said body tending to withdraw the firing pin 30 from said recess; a primer in position to be struck by said firing pin when same is withdrawn from said recess; a main pyrotechnic charge in said body; means arranged to ignite said pyrotechnic charge as a result of the functioning of said 35 primer; and safety means comprising a removable member constructed and arranged to engage said block to positively secure same in a position in which the apex of said cone is in axial alignment with the terminal end of said firing pin.
2. An igniter as described in claim 1, said body being formed with a socket wrench engaging surface, and said removable safety member being provided with a cross bar of greater length than the maximum diametral dimension of the wrench 40 engaging surface, the position of said cross bar being so related to the wrench engaging surface that it is impossible to engage a wrench therewith until said safety member has been removed.
